UNITED STATES PATENT OFFICE.

ALEXANDER H. EGE, OF MECHANICSBURG, PENNSYLVANIA.

RAILROAD-SWITCH.

SPECIFICATION forming part of Letters Patent No. 357,189, dated February 8, 1887.

Application filed February 15, 1884. Serial No. 120,811. (No model.)

To all whom it may concern:

Be it known that I, ALEXANDER H. EGE, a citizen of the United States, and a resident of Mechanicsburg, county of Cumberland, and 5 State of Pennsylvania, have invented certain new and useful Improvements in Railroad Switches and Frogs, of which the following is a specification.

My invention relates to improvements in 10 railroad switches and frogs, by which trains of cars in passing in either direction, whether upon the main track or siding, will be prevented from derailment under any and all circumstances arising from a misplaced switch, 15 and it has special reference to improvements in the switch patented to W. P. Dodson, June 6, 1882, No. 259,001.

In referring to the drawings, Figure 1 is a 20 plan view showing the main track and switch, with the latter set to the former in full lines and to the siding in dotted lines. Fig. 2 is a longitudinal section in line xx of Fig. 1. Fig. 3 is a plan showing the main track and siding with a frog to be used in connection with the 25 depressed track. Fig. 4 shows a longitudinal section on line yy of Fig. 3, with the part of deepest depression of the main track removed. Fig. 5 is a transverse section on the line $y'y'$ of Fig. 1 through the road-bed and rails, showing more particularly the arrangement of the 30 springs controlling the pointed rail. Figs. 6 and 7 are respectively plan and side views of a section of the main line, and showing my peculiar formation; and Fig. 8 is a plan view of the same, showing a wing-rail in position with the main-line rail.

The main track is indicated by the rails A' , one of which, as A , is formed with a depressed portion, as shown in the patent referred to, $B B'$ being the movable parts of the outside and inside rails, and $B^3 B^4$ the fixed parts of the same. In constructing tracks in accordance with that patent I found that when the tread of the wheels of the engine and cars 45 was of the width now generally used—say four inches—the wheels were liable to drop into the depression before the edge of the wheel-treads would bear sufficiently upon the siding or wing rail. To avoid this objection I form the 50 main-track rail in such a manner that the siding or wing rail may be brought so near to

the main-rail surface, against which the wheel-flange bears just before the depression commences, that at or before the point where the wheel reaches the depression its tread will be 55 partially supported upon the siding or wing rail. This may be accomplished in various ways, one of which is illustrated in Figs. 1, 6, 7, and 8.

Referring to Figs. 6 and 7, it will be seen 60 that the point or tongue c of the main rail at the beginning of the depression is in line with the inside edge of the rail, and to have this point over or in the plane of the web of the rail it is necessary to offset the web of the rail laterally, commencing at a point about c' , Figs. 6 and 7, so as to bring the web of the rail for a short distance, at or near the point c , practically in the plane of the inside edge or gage-line of the main rail. The crown or head is 70 then planed or otherwise cut away, so as to form the point, which will be directly over the web and in proper alignment with the remainder of the rail. The depression of the rail is preferably made before the planing or 75 cutting away of the crown, and may be made either before or after the web of the rail has been offset laterally. By this construction I am enabled to bring the siding or wing rail so near to the gage-line of the main track that 80 before the tread of the wheel passes off the main rail at the depressed portion it will bear sufficiently upon the siding or wing to be thoroughly supported.

In Fig. 8 I have shown a stationary siding-rail, B' , like that in the patent referred to, except by offsetting the web of the main rail and cutting it, as just described, I am enabled to bend the siding-rail B' , as shown, to bring its edge near the gage-line of the main track, so 90 that the wheel passing over the main track will be fully supported, and when the wheel passes to the siding it will also be supported, its flange crossing the main rail at the depressed portion. It is evident that the same 95 construction of the main rail, except that the rail is not shown as laterally bent, is used in the frog portion of the switch shown in Fig. 3, where r is the point, and i the depressed portion, of the main rail.

I have so far described my improved rail as 100 used in connection with a stationary siding or

wing rail, as shown in the patent above referred to. I have made a further improvement in connection with the rail by making the siding or wing rail movable, and preferably normally held in close lateral engagement with the main rail by spring-pressure or other equivalent means. In doing this I fasten one end of the wing or siding rail to the main rail or sleepers and bend the rail, so that its head 10 or crown projects partially over the depressed portion of the main rail and to bring the edge of the siding or wing rail into contact with the tapered edge of the point of the main rail, thereby affording an unbroken bearing for the 15 tread of the wheels.

Instead of bending the rail vertically to form the depression, a part of the rail may be cut away, as shown in dotted lines at q , Fig. 2, or the rail may be depressed to some extent and 20 the crown and part of the web cut away, as shown at q' , Fig. 4. In all these cases the main-line rail is continuous in part or in whole, and the carrying-surface of the main-line and siding or wing rails is always on the same 25 plane.

The location of the extremity of the switch-rail B is at a short remove from the commencement of the depression of said main rail A , as at f . At or near the point b said switch-rail 30 B is bent inwardly at such a curve as will admit of its head projecting partly over the head of the depressed part of the main rail until the point c is reached, when the curve is made to bear outward until it is brought into continuous prolongation with the permanent portion 35 of the siding at or near the point f' .

Since the natural resilience of the switch-rail B is an element that should also be taken into consideration when said rail is brought 40 into requisition in shunting, and is graduated by the length of the unspiked section thereof, it is not necessary that the section d' of the permanent siding-rail B' should be unduly prolonged toward the point c , but only extended so far that when in co-operation of said 45 resilience it will afford an interval between its extremity s and the contiguous main rail sufficient to admit of the intermediate passage of the wheel-flanges of a shunted train.

With regard to the construction of the switch-rail B' , I make the same pointed at its free end at an angle more or less acute, and pivoted at the opposite end as securely as necessary. When said switch-rail B' is set 50 for the main line by means of the switch-rod and lever, as in the case of a train passing up the main line, said switch-rail B' is required to perform the function of a guard-rail. As a re-enforcement in this relation I use one or 55 more guides or tongues, $v v$, to limit the inner range of said pointed rail B' , said guides being made to pass snugly under holders $m m$ or equivalent devices at their free ends, said 60 holders operating both as stops and as means 65 to prevent the tilting or twisting of the point-rail B' when subjected to the lateral pressure

of the engaging wheel-flanges. The transverse ends of the guides $v v$ are riveted or otherwise rigidly fastened to the web of the said point-rail. 70

In referring to the depression of the main-track rail A , it will be perceived that I limit its use to the oblique passage thereover of the wheel-flanges when shunting, and therefore the treads are made to roll upon the upper 75 surface of the switch-rail B under all circumstances, and not upon the concave surface of the main-track rail A . The curved switch-rail B in this connection having a lateral movement independent of the opposite switch-rail, B' , is not connected therewith by means of common actuating tie-bars, as is the case when both switch-rails are required to move in the same direction at the same time in opening and closing the switch. The switch-rail B may therefore be swiveled or rigidly fastened at the one extremity, f , to the main rail A , or at the other extremity, f' , in continuous prolongation of the permanent section d' of the siding, without any reference to the 90 point-switch B' ; hence the bars E and K , carrying the springs G and H , respectively, of the switch-rails B' and B , are swiveled or fastened at but one end to said switch-rails at the points h' and h . 95

The spring H in Fig. 1, having a thrust in but one direction, requires simply a single terminal nut, k , and a stop, k' , to control the pressure of the same upon the opening and closing of the switch. 100

If by frequent use it be found that the switch-rail B has lost a portion of its natural resilience, a double-crank shaft and connecting switch-rods may be used, as shown in Fig. 1 in dotted lines, one of which rods is fastened 105 to the switch-rail B' and the other to the rail B , and by these means the switch is operated as may be desired; but in this case, to make the switch automatic, springs must be used in connection with each rod. 110

The operation of the spring H or its equivalent is confined to the function of yielding to the lateral pressure of the wheel-flanges of a train during its passage from or onto the siding, and also, after said passage, of forcing the 115 switch-rail B into lateral contact with the main rail A , in order to supply the desired bearing for the wheel-treads when moving over the main line, and at the same time to restore, as much as possible, the continuity of said main 120 rail, otherwise somewhat interrupted by the contiguous depression of the same.

In directing the attention further to the action of the wheel-flanges on the right upon their arrival at the intersection of the switch-rail B' with the prolongation of the main-track rail A at the point of greatest depression, i , we perceive the same easy and uninterrupted 125 passage of the wheel-flanges of the in or out going train over the main rail A , attended by 130 a similar lateral pressure of the same against the head of the laterally-moving wing-rail B' ,

as obtains in the analogous case of the switch. The wing-rail B' being pivoted, swiveled, or otherwise fastened at its extremity d , (a bolt, M, having a double spring-bearing being shown,) co-operates with the yielding spring G' , and thereby admits of the uninterrupted transit of the wheel-flanges between said wing-rail and the pointed head of the main rail or tongue of the frog and the top of the incline r . The throat of said frog is thus seen to be the place of greatest depression, i , the tongue said point r , and the wing-rail the spring-actuated rail B' , which, in connection with the lateral supporting continuous main-track rail A, afford the necessary bearings of both the main line and siding to secure the desired safe passage of a train thereover in any desired direction.

The advantage gained by and the necessity for the pointing of the head of the main-track rail A at the beginning of the depression, at one end thereof at least, is shown by observing the engagement of the wheel-treads in their passage over the main line within the limits both of the switch and frog. In consequence of offsetting the web of the rail laterally, and then planing away the lateral edges of the head of the main-track rail in vertical planes converging to the web at the point of flexure, I am able to bring the inner or gage line of the said main-track rail into such close lateral proximity to its contiguous siding or wing rail that the wheel-treads extend so far beyond the outer lateral limits of the pointed head of the main-track rail that they roll with a safe bearing upon the horizontal upper surface of both of said rails before passing within the longitudinal limits of the depression. The treads of car-wheels being of a limited breadth,

said pointing of the head of the main-track rail affords safe means of transit to trains over the main line, or from the same to the siding, and vice versa.

The automatic action of the spring-actuated rails of the switch and frog when the switch is set wrong to a train engaging therewith is so obvious as to require no description, and hence need not be referred to in detail.

What I claim as new, and desire to secure by Letters Patent, is—

1. The laterally-bent crown-pointed depressed rail A of the main track, and the rail A' of the same, in combination with the movable switch-rail B, and the pointed and movable switch-rail B' of the siding, as and for the purpose set forth. 50

2. The combination, with the main-track rails A and A', the former crown-pointed and depressed, the movable switch-rail B, and the pointed and movable switch-rail B' of the siding, of suitable springs for actuating the switch-rails B and B' laterally, substantially as described. 55

3. The combination, with the main-track rail A, having two crown-pointed and depressed portions, of the spring-actuated siding and wing rails, substantially as described. 65

4. The combination, with a continuous main-line rail, of a spring-actuated outside and independently-moving siding-rail, substantially as and for the purpose set forth. 70

In testimony whereof I affix my signature in presence of two witnesses.

ALEXANDER H. EGE.
